TUBULAR TAPERED CONNECTORS

Maurus C. Logan, Elizabeth, and David J. Crimmins,
Nutley, N.J., assignors to The Thomas & Betts Co., a
corporation of New Jersey

Filed Mar. 14, 1963, Ser. No. 265,203
4 Claims. (Cl. 174—75)

This invention relates to a connector to be formed on the bared end extending from an electrical conductor so as to define the tapered connector end thereto, to facilitate electrical connection of the conductor to another conductor or electrical element.

Pursuant to the invention, the connector is essentially electrically and physically homogeneously united with the bared end of an electrical conductor wire encompassed therein, providing a connector of novel construction such that repeated use thereof may be made without damage, distortion, power loss or failure. The connector is further well adapted for use in many applications wherein limited space is available therefor and is highly durable and reliable in use.

The connector is formed from a flat blank into a tapered portion which is (at least partially) essentially solid in cross section with the bare wire end on which it is assembled.

Further pursuant to the invention, the connector is formed from a blank provided with longitudinal edges transversely complementarily formed for interfitting on closing the blank, thus resisting and preventing axial distortion of the connector in use.

The drawings, illustrating procedures and devices useful in carrying out the invention, and the description below, are exemplary only of the invention, which shall be deemed to cover all other devices and procedures coming within the scope and purview of the appended claims.

In the drawings, wherein similar reference characters indicate like parts:

FIG. 1 is a partly fragmentary, plan view of a connector embodying the invention.

FIG. 2 is a similar view of another form thereof.

FIG. 3 is a vertical, longitudinal, sectional view thereof, taken at line 3—3 of FIG. 1.

FIG. 4 is a fragmentary, top plan view of another form of connector embodying the invention.

FIG. 5 is a fragmentary partly sectional view taken at line 5—5 of FIG. 7, of a connector member of this invention, engaging a complementarily formed member 28.

FIG. 6 is an enlarged, fragmentary, vertical sectional view, showing such connector inserted into a conductor-member by an applying tool, and further showing a second connector, embodying the invention, about to be so inserted.

FIG. 7 is a fragmentary, plan view of a member 28 to which a plurality of conductors are shown secured.

FIG. 8 is a fragmentary, sectional view of a conductor member, showing a connector of this invention being inserted therein.

FIG. 9 is a partly fragmentary, perspective view of a continuous strip forming procedure which may be used in the manufacture of the connector of this invention, and

FIG. 10 is a transverse, sectional view of a connector formed with the tab 36 (FIG. 9) extending substantially from a longitudinal edge with the tab folded inwardly of the connector.

FIG. 11 is a plan view of a blank used in the forming of the connector of the present invention.

As shown in the drawings, the connector 10 (FIG. 1) of this invention is formed from a pre-cut elongated blank 11 (FIGS. 9 and 11) preferably of metal, alloy or

2

other materials which may be coated or plated if desired and which may be self conducting or may be formed, plated or coated with a conducting material to render the same conductive or to improve the conductivity thereof. The blank has opposite longitudinal edges 12, 13 (FIGS. 1, 4, 9, 11) so formed (as below described) that, when the blank is closed, it will define a tapered, longitudinal tubular form, as indicated at 14 in FIG. 9 and the longitudinal edges 12 and 13 will interfit and be disposed contiguously. The blank is formed (FIGS. 1 and 11) with a major portion 15 thereof having the longitudinal edges thereof so contoured to define, when the blank is rolled or otherwise formed to closed position, an elongated tapered end; the remaining, short end portion 16 (FIGS. 9 and 11) forms, on closing the blank, a ring portion 17 which may have a slot 18 therein for (FIG. 6) inspection and checking purposes. The connector is designed for application to the bared wire end 19 (FIG. 3) extending through and projecting from end 20 of a sheath or length of insulated conductor wire or cable 21. The bared end 19 may be single wire strand or a plurality of strands or cable as shown. The bare end 19 is wedged and gathered tightly in the so-formed tapered end of the blank in the closing operation as shown in FIG. 25 and the conductor may be crimped at at least the ring end 17 of the blank if desired.

The bared wire end 19 is positioned initially on the major end 15 of the blank (center blank, FIG. 9) with the end 20 of the insulation sheath 21 positioned on the ring portion 17 of the blank and then the blank is folded or formed over the bared wire end 19 as by rolling the blank to tubular tapered form 14 (FIG. 8) to close the blank tightly over said bared wire end 19, the ring 17 gripping the end 20 of the insulated conductor length 21.

Thus, the wire end 19 and the tapered portion 14 of the connector are essentially homogeneously electrically united, so that current will flow essentially directly from the wire end 19 to the other conductor member of the block 28 into which the end 15 is inserted, without any appreciable power loss or electrical resistance. When the blank is so formed to final tubular tapered form, the end 16 (FIG. 9) is, as above noted, formed as an encircling ring 17 over the end 20 of the wire enclosing insulating sheath 21.

While any forming operation may be followed in carrying out the invention, a convenient procedure is illustrated in FIG. 9, wherein the blanks 11 are shown initially connected to an elongated feed strip 25 by the severable tabs 26, as by initially blanking a flat sheet of metal to that form; concurrently with the forming of the connector to the longitudinal tubular form 14 or immediately thereafter, the tab 26 may be severed, disconnecting the blank at tab 26 from the elongated feed strip 25. In this procedure, the blank may be initially partially formed to generally channeled longitudinal configuration to facilitate positioning the bared wire end 19 and the insulating sheath 20 thereon, preparatory to the step of forming blank to its longitudinal tubular form 14 and severing the same from the feed strip 25.

In further re-enforcement of the connector, to enable repeated use thereof without distortion, and greatly enhancing the efficacy and reliability thereof in use, the marginal longitudinal edges 12, 12 of the major portion 15 of the connector may be provided with complementary transversely sinuous or transversely disposed interfitting portions which may be formed as alternate outwardly and inwardly extending curved portions 31, 32, 33 (FIG. 1, 39, 40, FIG. 2) thereof disposed generally transversely of the longitudinal axis of the major portion 15 of the connector and thus interfitting in the final formation

thereof to enhance the closure action of the blank on the wire end and to effectively counter and resist stresses and strains and preserve the tapered tubular form and accurate functioning of the connector. FIG. 4 shows a single outwardly extending rectangular portion 34 extending beyond one of the longitudinal edges of the major portion 15 of the connector and received in a complementarily formed recess 35 in the other longitudinal edge thereof, and FIG. 2 shows a tapered outwardly extending portion 39 received in a complementarily formed recess 40.

As shown in FIG. 9, the elongated fingers 36, 37, may be formed to extend from one or both longitudinal edges of the blank to lessen the diameter of the blank, so that when the blank is folded and formed (as shown in FIGS. 9, 1-5) and said fingers are folded inwardly of the blank (FIG. 10), it will hold a bare wire end of such lesser diameter.

The blanks may be so formed with such fingers alternately in the series of blanks (as in FIG. 9) to adapt those (so formed) blanks to use with bare wire ends of substantially lesser diameters than those with which the blanks are customarily used. The blanks may be formed uniformly with such fingers when it is desired to have all blanks adaptable to such further use. The fingers may be weakened as noted at 38, 38' (FIG. 9) so that the fingers may be broken off where, after they are so formed, it is not desired to use them. The blank may be further provided at the juncture of the major and minor portions (15 and 16) thereof, with a transversely formed continuous projection 27 (FIG. 1). When the blank is formed to final tubular form, the connector may be positioned in any desired block member 28, which may be provided with tapered engaging conductor means such as 29 (FIG. 5), the parts being complementarily formed so that the connector may be driven into frictional engagement therewith by any suitable tool, such as indicated at 30 in FIG. 8. The tool presses against the transversely formed projection 27 to that end and drives the connector 10 into frictional engagement with the tapered means 29. The latter may connect the members 10 with others (FIG. 6) or with other components or equipment according to the end use desired. It will be noted that longitudinal axial length of the ring portion 17 is very short, thus substantially reducing the length available for applying right angle tilting or damaging leverage and reducing the likelihood of damage to the pin which usually occurs at the point of juncture of the ring and tapered portions, or to the pin and socket joint itself. As will be noted from FIG. 7 the construction of this invention additionally enables the utilization of such connectors in many applications wherein the space available between adjacent pieces of equipment 30 is extremely limited.

It will be noted from FIG. 3 that the bared wire end 19 of the conductor wire is, in the connector of this invention, directly aligned with the major tapered end portion 15 thereof and is in direct physically compressed engagement therewith so that, upon insertion of the connector into the conductor members 28, current will flow in an essentially straight line, from the bared wire 19 to the conductor member 28, reducing to an essential minimum any possibility of power loss and providing a positive and constant direct electrical connection. Although the blank of which the connector is formed is of relatively small cross-sectional dimensions, the tapered tubular form 14 of the finished connector thus formed de-

4
fines an essentially rigid, solid cross section continuous with the contained, bared wire end 19 at the point of electrical connection.

Having thus described our invention, what we claim as new and desire to secure by Letters Patent are:

1. In a one-piece blank formable into a terminal connector for an insulated electrical conductor cable, the combination comprising, an elongated flat blank including opposed complementary longitudinal edges, said complementary edges including transversely disposed interfitting means registrable when said blank is formed into a connector, each of said longitudinal edges diverging with respect to the other to define a major tapered portion terminating at one end of said blank when the blank is formed into a connector, a conductor receiving socket within said major tapered portion, means defining a substantially cylindrical minor ring portion integral with said tapered portion and extending therefrom at the end opposite said tapered hollow portion to receive an insulated covered portion of said conductor when said blank is formed into a connector, and finger means formed on at least one longitudinal edge of said blank and extending outwardly therefrom, said finger selectively foldable with respect to said edge to a position within said tapered hollow portion when said blank is formed into a connector to decrease the interior diameter of said hollow tapered portion to accommodate conductors of reduced diameter.

2. The one-piece blank formable into an electrical connector defined by claim 1, wherein said blank includes means defining a transversely disposed projection at the juncture of said major and minor portions thereof when said blank is formed into a connector.

3. The one-piece blank formable into an electrical connector defined by claim 1, wherein said finger means are formed on both longitudinal edges of said blank to extend outwardly therefrom.

4. The one-piece blank formable into an electrical connector defined by claim 1, wherein said interfitting means include at least one outwardly extending and at least one complementary inwardly extending sinuous portion.
